CARRIER SUPPORT FOR RECIPROCATING CONVEYERS

William W. Sloane, Chicago, Ill., assignor to Goodman Manufacturing Company, Chicago, Ill., a corporation of Illinois

Application November 4, 1932, Serial No. 641,144

2 Claims. (Cl. 198—220)

This invention relates to improvements in carrier supports for conveyer troughs of the shaker or reciprocatory type.

The principal objects of the invention are to provide a new and improved carrier support for shaker conveyer troughs wherein the trough is carried for reciprocable movement on anti-friction rollers and has free rocking movement with respect to the carrier support permitting said carrier support to be used where the mine bottom is uneven.

Other objects of my invention will appear from time to time as the following specification proceeds.

15 My invention may be more clearly understood with reference to the accompanying drawing wherein:

Figure 1 is a top plan view of a conveyer trough carried by a device embodying my invention with parts of the conveyer trough broken away and in section to more clearly show the details of my invention;

20 Figure 2 is a sectional view taken substantially along line 2—2 of Figure 1;

25 Figure 3 is a sectional view taken substantially along line 3—3 of Figure 1;

Figure 4 is an enlarged sectional view taken substantially along line 4—4 of Figure 1;

30 Figure 5 is a view showing a modified form of my invention; and

Figure 6 is an enlarged sectional view taken substantially along line 6—6 of Figure 5.

Like numerals refer to like parts throughout the various figures.

35 Referring now in particular to the details shown in the drawing, a conveyer trough 11 is provided. Said conveyer trough is of an ordinary type well known to those skilled in the art and is adapted to be supported by a carrier, generally indicated by reference character 12.

40 Suitable means are provided for effecting an accelerated and retarded movement to the conveyer trough 11 for moving material therealong, which means is of an ordinary type well known to those skilled in the art and is not herein shown in detail since it is no portion of my present invention.

45 With reference to the details of the carrier 12, said carrier includes a frame member comprising a plurality of parallel spaced members, herein preferably shown as being angle irons 14, 14, extending transversely of the conveyer trough 11 and connected together by a pair of parallel spaced 55 guide members 15, 15 extending generally longi-

tudinally of said conveyer trough adjacent opposite sides thereof.

The angle irons 14, 14 are so arranged that one of each of their legs extends downwardly and is adapted to form a support for the carrier 12, 60 and their other legs extend outwardly from the transverse center line thereof. The depending legs of said angle irons may engage the ground or said angle irons may be engaged with suitable mine ties, as is clearly shown in Figure 2. Suitable means may be provided for holding said carrier to the mine ties, which may be suitable spikes passing through apertures provided in the ends thereof in a usual manner. Said ties may be held from movement by means of suitable mine 65 jacks interposed between said ties and the sides or roof of the mine in a manner well known to those skilled in the art.

70 The guide members 15, 15 are of an angular shape and have one of their legs extending towards the longitudinal center line of the conveyer trough 11 and their opposite legs extending angularly upwardly and outwardly with respect to said longitudinal center line of said conveyer trough to form a guide in which suitable roller 75 devices 17, 17 may ride. Suitable stops are provided on the ends of said guide members, which may be of any type but which are herein preferably shown as being plates 18, 18 secured to the ends thereof in a suitable manner, such as 80 welding.

75 It should be noted that the upper legs of the angles 15, 15 extend angularly outwardly from the point where the rollers 17, 17 ride on the horizontal legs of said angles. When the trough is in misalignment, end thrust is taken adjacent the rim of the roller which is the portion of the roller having a rolling motion. This arrangement reduces frictional resistance between the rollers and guides and wear on the rollers in 90 that sliding contact between said rollers and the sides of the angles is minimized.

95 The roller devices 17, 17 are of an anti-friction type and include an inner race 19 having an inwardly extending stud 20 formed integral therewith, an outer race 21, suitable balls riding in said inner and outer races, and an annular housing 23 therefor, which housing also forms a roller and rolls along the guide member 15.

100 The roller devices 17, 17 are connected together by means of a suitable transversely extending carrier member 24 and with said carrier member form a carriage for the conveyer trough 11. Said carrier member has upturned ends 25, 25 adapted to be secured to the studs 20 by means of suit- 105

able nuts 26, 26 in an ordinary manner. Said carrier member has a raised central portion, the upper surface of which is beneath the axis of rotation of the roller devices 17, which portion is 5 adapted to support the conveyer trough 11. Said carrier member is provided with a relatively long socket 27 formed therein of substantially the same length as the width of the bottom of the conveyer trough 11 for receiving a depending 10 stem 29 of a T member 30 secured to the under-surface of said conveyer trough and of substantially the same length as the width of the bottom portion of said conveyer trough. The underportion of the cross of the T member 30 15 is adapted to rest on the upper surface of said carrier member and be supported thereby so that said carrier member will pivot about the axes of the roller devices 17, 17 when said conveyer trough is pivoted with respect to the angle irons 20 14, 14. It should be noted that in cases where said conveyer trough is supported in such a manner that it does not rest on said carrier member, that the stem 29 of the T member 30 will reciprocably move said carrier member upon reciprocation thereof. Such a condition, however, is not desirable inasmuch as the function 25 of the carrier 12 is to form a movable support for said conveyer trough in such a manner that different angular relations between said conveyer trough and the carrier frame are compensated 30 for due to the fact that said carrier member is pivotally movable about the axes of the roller devices 17, 17.

It may thus be seen that the conveyer trough 35 11 is supported by the roller devices 17, 17 for movement in the guide members 15 and for pivotal movement about the axes of rotation of said roller devices. Thus the carrier 12 may be set on a mine bottom which is of a different angle 40 than said conveyer trough, and may effectively support said conveyer trough in varying angular positions with respect thereto. It should also be noted that due to the fact that the portion 45 of the transversely extending carrier member 24 which supports said conveyer trough is beneath the axes of pivotal movement of the roller devices 17, 17, that a supporting means for said conveyer trough has been provided which is of a minimum vertical height and which permits 50 the combined height of the carrier 12 and conveyer trough 11 to be reduced to a minimum.

With reference now in particular to Figures 5 and 6, and a modified form of my invention, a carriage for the conveyer trough 11 is formed by 55 means of a transversely extending carrier member 31 which has pivotal connection with the roller devices 17, 17 adjacent their inner ends for pivotal movement about the axes of rotation

thereof. Said transversely extending carrier member has an upstanding central web 33, the contour of the upper surface of which conforms substantially to the form of the conveyer trough. Said upstanding central web of said carrier member is adapted to fit between suitable connecting members 34, 34 secured to the ends of adjacent conveyer troughs for connecting said conveyer troughs together. Suitable sleeves 35, 35 are adapted to pass through suitable apertures in the upstanding central web of said carrier member. Suitable connecting bolts 36, 36 are adapted to pass therethrough and secure adjacent conveyer troughs together. 80 85 90

Thus a rigid connection between the carrier member 31 and adjacent conveyer troughs has been provided which permits said conveyer troughs to be carried for reciprocable movement on suitable anti-friction roller devices and permits said troughs to be pivotally adjusted about 95 the axis of said roller devices to compensate for uneven bottom conditions. 95

While I have herein shown and described one form in which my invention may be embodied, it will be understood that the construction and 100 arrangement of the parts may be altered without departing from the spirit and scope thereof. Furthermore, I do not wish to be understood as limiting myself to the specific construction illustrated herein, excepting as specifically limited in 105 the appended claims.

I claim as my invention:

1. In a shaker conveyer and in combination with a conveyer trough, a carrier therefor including a pair of anti-friction roller devices, a 110 supporting member carrying said anti-friction roller devices for free rotation with respect to each other, means for supporting said conveyer trough on said supporting member, and a track for said rollers including parallel spaced guide 115 members having retaining members extending outwardly away from the point of contact of the rim of said rollers with said guide members.

2. In a shaker conveyer and in combination with a conveyer trough, a carrier therefor including a pair of anti-friction roller devices, a supporting member carrying said anti-friction roller devices for free rotation with respect to each other, means for supporting said conveyer trough on said supporting member, and a track 120 125 for said rollers including parallel spaced guide members comprising angles having inwardly extending horizontal legs forming a generally horizontal track for said rollers and upwardly extending legs extending angularly away from the 130 point of contact of the rim of said rollers with said track.

WILLIAM W. SLOANE.
